UNITED STATES PATENT OFFICE.

ROBERT FULGOR, FREDERICK S. MURRAY, AND WALTER MURRAY, OF NEW YORK, N. Y.

AMUSEMENT APPARATUS.

961,947.

Specification of Letters Patent. Patented June 21, 1910.

Application filed November 10, 1909. Serial No. 527,157

To all whom it may concern:

Be it known that we, ROBERT FULGOR, FREDERICK S. MURRAY, and WALTER MURRAY, citizens of the United States, and residents of the borough of Manhattan, city, county, and State of New York, have invented certain new and useful Improvements in Amusement Apparatus, of which the following is a specification.

10 This invention relates to an amusement apparatus designed to reflect upon a screen the image of a subject and particularly the image of a living subject.

15 The apparatus also provides for causing the reflected image to move on the screen, such movement answering to a certain movement, but dissimilar movement, of a subject.

20 The invention consists in the apparatus and features shown in the drawings and as hereinafter described and claimed.

25 In the accompanying drawings forming part of this specification, and in which like reference numerals designate corresponding parts in the several figures,--Figure 1 is a plan view partly broken away and partly in section; Fig. 2 is a sectional elevation on the line 2--2 of Fig. 1; Fig. 3 is a rear elevation looking toward the left of Fig. 1; Fig. 4 is a sectional plan view on the line 30 4--4 of Fig. 3; Fig. 5 is a sectional elevation on the line 5--5 of Fig. 1; and Fig. 6 is a diagram of the electrical circuits and connections.

Referring now more particularly to the 35 apparatus as shown in the drawings, 1 is a cabinet designed to rotate or turn about a fixed center having an opening 2 in its lower side and a curtain 3 hanging down from the cabinet and a part of which closes the front 40 end of the cabinet.

45 4 is a pivot block secured to the lower side of the cabinet and having a conical recess to receive the conical end of the tubular pedestal 5 whose lower end is fixed to a base 50 6. The block 4 forms the upper end of a tubular sleeve 7 surrounding the pedestal 5 and provided at its lower end with a spacing ring 8.

9 is a support for the seat 10 on which the 55 subject may sit whose image is to be thrown upon the screen. The support 9 surrounds the sleeve 7 and is supported in place by

hanger rods 11 whose upper ends are fastened to a collar 11^a screwed on the sleeve 7 and to which the cabinet is secured. 55

12 is a reflector within the cabinet having a hinged connection 13 with the lower side thereof. This reflector is so mounted as to be oblique to the axis of its own rotation and that of the cabinet. The reflector fits 60 in between the two wings 14 and 15 at the rear of the cabinet. Its obliquity may be adjusted on the hinge 13 by a set screw 16 carried by the reflector and adapted to engage the wing 14 so as to hold the reflector 65 in position.

17 is an arc-shaped extension from the reflector's frame whose purpose is to prevent the escape from the cabinet of light above the reflector when the latter is tilted 70 back from its position as shown in Fig. 2.

The reflector 12 may be called the primary reflector.

18 is another hinged reflector which may be called the secondary reflector. It is 75 maintained in co-operative relation with the primary reflector so as to receive from the reflector 12 the reflected image and throw it upon the screen. The reflector 18 is mounted in the axis of rotation of the reflector 12 and of the cabinet 1 and is oblique to this axis. It forms the upper end of the sleeve 19 which is provided with an opening 20 through which the light rays from the reflector 18 pass forward to the screen. The 80 sleeve 19 is loosely mounted on the tube 21 which is provided with lenses 22 and 23. 85

24 is a gear wheel fixed to the sleeve 19 for a purpose hereinafter described.

25 is a pivot whereby the two sections of 90 the tube 21 may be moved for the adjustment of the lenses 22 and 23.

26 and 27 are two lamp chambers located on opposite sides of the reflector 12. They are carried by the cabinet and open thereinto in advance of said reflector. Each is provided with an arc-lamp 28 and each is provided with a lens 29 and a water screen 30 through which the light rays pass before entering the cabinet. The water screen consists of a chamber containing water and having its front and rear walls made of translucent material, such as glass. The water screen serves to absorb the heat rays 100.

from the lamp. The lenses serve to converge the light rays upon the subject occupying a position in the cabinet in front of the reflector 12. The subject may sit upon 5 the seat 10 with the head thrust inside the cabinet through the opening 2.

Any suitable means may be employed for rotating the reflector 12 and cabinet and for holding the reflector 18 against rotation. 10 As shown in the drawings a motor 31 is employed for rotating the cabinet and reflector. Its shaft carries a pinion 32 which meshes with a gear wheel 33 fixed on the pedestal 5. Meshing with the gear wheel 33 15 is a pinion 34 carried on the shaft 35 which turns in bearings in the support 9 and in the bottom of the cabinet 1. The upper end of the shaft carries a pinion 36 which meshes with the gear wheel 24. When the motor 20 operates the pinion 32 travels around the gear wheel 33 causing the support 9, sleeve 7 and cabinet to also turn about the pedestal 5. This movement causes the shaft 35 to travel around the pedestal with the support 25 9 and cabinet and imparts a rotary movement to the shaft through the gear wheel 33 and pinion 34. As the shaft 35 rotates, its pinion 36 travels around the gear wheel 24 and prevents it and the reflector 18 from 30 turning. Gear wheels 24 and 33 have the same diameter and pinions 34 and 36 have also the same diameter. It will thus be seen that the reflector 18 is kept facing in the same general direction, notwithstanding 35 the rotation of reflector 12 and cabinet. When the subject is, for example, a woman, seated on the seat 10, her head will extend into the cabinet. As she sits opposite the reflector 12, her image will be thereby reflected on to the reflector 18 and thrown from thence upon the screen 63. As the cabinet rotates, the reflected image of the subject's face will change its position on the reflector 18 and consequently on the screen, 40 the face having a rotary movement on the reflector 18 and on the screen due to the changing relation of the reflectors. 45

The lamps 28 are employed to illuminate the subject whose image is to be reflected. 50 It is preferred to employ arc-lamps for this purpose and the apparatus is provided with circuits for the lamps including switches and resistances carried by the support 9. For this purpose circuit wires pass into the 55 tubular pedestal 5 from the source of current and are connected, respectively, to insulated contact rings 37 and 38 carried on the outside of pedestal 5.

39 and 40 are contact brushes secured on 59 the outside of the sleeve 7 and passing through apertures in the sleeve into contact with the rings 37 and 38. The contact brushes 39 and 40 are connected by wires 41

and 42 with plug socket 43. These brushes are also connected by wires 44 and 45 with 65 plug socket 46.

47 and 48 are plugs for the sockets 43 and 46 and are respectively connected with the lamps in the lamp chambers 26 and 27 through resistances 49 and 50. When these 70 plugs are inserted in their sockets, the lamps are in circuit through the resistances which are in series with lamps.

51 and 52 are additional plugs connected with resistances 53 and 54. The socket 55 75 for the plug 51 is connected with resistance 49. When the plugs 47 and 51 are in their sockets, the resistances 49 and 53 are in multiple with their connected lamp 28.

56 is a socket for the plug 52 and connected with resistance 50 whereby the resistances 54 and 50 may be connected in multiple with their lamp 28.

57 and 58 are standards carried by the support 9 for supporting the resistances and 85 the plug sockets.

The top and side walls of the cabinet 1 are formed of a series of separated overlapping plates arranged to form tortuous passages between adjoining plates so that the 90 passage of light rays through the wall may be obstructed particularly the light rays projected into the cabinet by the lamps 28, the passage of sound waves being permitted through these tortuous passages between the 95 plates. In this way the light thrown upon the subject within the cabinet is intensified and the voice of the subject, either in singing or speaking, may be readily heard outside the cabinet without serious diminution. 100

59 indicates the plates forming the top wall of the cabinet. These plates are arranged parallel to each other and are fastened together by the rods 60. The side walls of the cabinet are formed by similar 105 plates 61 similarly arranged and are fastened together by the rods 62.

It will be noted that the plates of the several walls slant in the same general direction, their inner edges pointing toward the 110 rear of the cabinet and away from the lamp chambers 26 and 27 which open into the cabinet at the front side thereof.

What is claimed and what is desired to be secured by Letters Patent is:— 115

1. In an amusement apparatus, the combination of a rotatable primary reflector fixed in a position oblique to its axis of rotation; a secondary reflector maintained in co-operative relation with said primary reflector; and a support for the subject arranged to rotate with said primary reflector. 120

2. In an amusement apparatus, the combination of a rotatable cabinet; a primary reflector carried thereby and mounted oblique 125 to the axis of rotation; and a secondary re-

lector maintained in coöperative relation with said primary reflector and facing in one and the same general direction.

3. In an amusement apparatus, the combination of a rotatable cabinet; a primary reflector carried thereby and mounted oblique to the axis of rotation; a secondary reflector maintained in coöperative relation with said primary reflector and facing in one and the same general direction; and means for artificially lighting said cabinet carried thereby.

4. In an amusement apparatus, the combination of a rotatable cabinet; a primary reflector carried thereby and mounted oblique to the axis of rotation; a secondary reflector maintained in coöperative relation with said primary reflector and facing in one and the same general direction; means for artificially lighting said cabinet carried thereby; and a seat mounted to move with said cabinet.

5. In an amusement apparatus, the combination of a rotatable cabinet; a primary reflector carried thereby and mounted oblique to the axis of rotation; a secondary reflector carried by said cabinet and having a pivotal connection therewith; means for rotating said cabinet; and means for holding the secondary reflector against rotation.

6. In an amusement apparatus, the combination of a rotatable cabinet; a primary reflector carried thereby and mounted oblique to the axis of rotation; a secondary reflector carried by said cabinet and having a pivotal connection therewith; means for rotating said cabinet; means for holding the secondary reflector against rotation; and a seat beneath said cabinet and rotating therewith.

7. In an amusement apparatus, the combination of a rotatable cabinet; a primary reflector carried thereby and mounted oblique to the axis of rotation; a secondary reflector maintained in coöperative relation with said primary reflector and facing in one and the same general direction; and lamp chambers provided with lamps carried by said cabinet and opening therewith in advance of said primary reflector.

8. In an amusement apparatus, the combination of a rotatable cabinet; a primary reflector carried thereby and mounted oblique to the axis of rotation; a secondary reflector carried by said cabinet and having a pivotal connection therewith; means for rotating said cabinet; means for holding the secondary reflector against rotation; and lamp chambers provided with lamps carried by said cabinet and opening therewith in advance of said primary reflector.

9. In an amusement apparatus, the combination of a rotatable cabinet; a primary reflector carried thereby and mounted oblique to the axis of rotation; a secondary reflector

maintained in coöperative relation with said primary reflector and facing in one and the same general direction; lamp chambers provided with lamps carried by said cabinet and opening therewith in advance of said primary reflector; and a seat beneath said cabinet and rotating therewith.

70

10. In an amusement apparatus, the combination of a rotatable cabinet; a primary reflector carried thereby and mounted oblique to the axis of rotation; a secondary reflector maintained in coöperative relation with said primary reflector and facing in one and the same general direction; lamp chambers provided with electric lamps carried by said cabinet and opening therewith in advance of said primary reflector; and electric circuits for said lamps including resistances and switches mounted to rotate with said cabinet.

75

11. In an amusement apparatus, the combination of a fixed pedestal; a seat support and cabinet mounted to rotate on said pedestal; a primary reflector carried by said cabinet and mounted oblique to the axis of rotation; a secondary reflector carried by said cabinet and having a pivotal connection therewith; means for turning said seat support and cabinet on said pedestal; and means for holding said secondary reflector so as to face in one and the same general direction.

85

12. In an amusement apparatus, the combination of a fixed pedestal; a seat support and cabinet mounted to rotate on said pedestal; a primary reflector carried by said cabinet and mounted oblique to the axis of rotation; a secondary reflector carried by said cabinet and having a pivotal connection therewith; lamp chambers provided with electric lamps carried by said cabinet and opening therewith in advance of said primary reflector; means for turning said seat support and cabinet on said pedestal; and means for holding said secondary reflector so as to face in one and the same general direction.

90

13. In an amusement apparatus, the combination of a fixed pedestal; a seat support and cabinet mounted to rotate on said pedestal; a primary reflector carried by said cabinet and mounted oblique to the axis of rotation; a secondary reflector carried by said cabinet and having a pivotal connection therewith; lamp chambers provided with electric lamps carried by said cabinet and opening therewith in advance of said primary reflector; means for turning said seat support and cabinet on said pedestal; means for holding said secondary reflector so as to face in one and the same general direction; and electric circuits for said lamps including resistances and switches carried on said seat support.

95

100

105

110

115

120

125

14. In an amusement apparatus, the combination of a reflector; a support therefor with which the reflector has a pivotal connection; a pedestal in axial alignment with 5 said reflector and on which said support is rotatably mounted; a gear wheel immovably fixed on said pedestal; a gear wheel connected with said reflector; a shaft carried by said support; and pinions on said 10 shaft meshing with said gear wheels, whereby as said support turns said reflector is held against rotation.
15. In an amusement apparatus, a cabinet for the purpose set forth having its walls 15 formed of a series of separated overlapping plates arranged to form tortuous passages between adjoining plates, whereby the passage of light rays is obstructed and the passage of sound waves is permitted through 20 said tortuous passages.
16. In an amusement apparatus, a cabinet for the purpose set forth having its walls formed of a series of separated overlapping plates arranged to form tortuous passages 25 between adjoining plates, said plates slanting in the one and general direction and those of each wall being parallel with each other, whereby the passage of light rays is obstructed and the passage of sound waves is 30 permitted through said tortuous passages.
17. In an amusement apparatus, a cabinet for the purpose set forth having its walls formed of a series of separated overlapping plates arranged to form tortuous passages 35 between adjoining plates, whereby the passage of light rays is obstructed and the passage of sound waves is permitted through said tortuous passages, combined with angularly disposed lamp chambers opening 40 into said cabinet.
18. In an amusement apparatus, a cabinet for the purpose set forth having its walls formed of a series of separated overlapping plates arranged to form tortuous passages 45 between adjoining plates, said plates slanting in the general direction and those of each wall being parallel with each other, whereby the passage of light rays is obstructed and the passage of sound waves is permitted through said tortuous passages, 50 combined with angularly disposed lamp chambers opening into said cabinet.

In testimony whereof, we have signed our names to this specification, in the presence of two subscribing witnesses.
